J. M. Wright,

Atty.

UNITED STATES PATENT OFFICE.

ALFRED BROWN, OF CROCKETT, CALIFORNIA.

GARMENT-CREASER.

1,324,004.

Specification of Letters Patent. Patented Dec. 2, 1919.

Application filed January 3, 1918. Serial No. 210,126.

To all whom it may concern:

Be it known that I, ALFRED BROWN, a citizen of the United States, residing at Crockett, in the county of Contra Costa and State of California, have invented new and useful Improvements in Garment-Creasers, of which the following is a specification.

The object of the present invention is to provide a simple, convenient and effective device which can be used by the wearer of a garment for forming creases therein.

In the accompanying drawing, Figure 1 is a side view of a coat showing my invention applied thereto; Fig. 2 is a similar view of a pair of trousers; Fig. 3 is a similar view of a waistcoat; Fig. 4 is an edge view of a wooden strip forming part of my invention, showing also a stretcher pin applied thereto; Fig. 5 is a perspective view of a ring forming part of the invention; Fig. 6 is a similar view of a retainer pin; Fig. 7 is a similar view of a stretcher pin.

Referring to the drawing, 1 indicates a thin flat strip of hard wood of much greater length than width. For forming a crease or for pressing the edge of a garment flat a pair of such strips is employed. To form a crease, as, for instance, in front of either leg of a pair of trousers, the cloth is folded and the two strips of a pair are placed on opposite sides of the fold and held securely in that position by means of rings or coils 2 of stout spring wire. Each ring or coil extends about one and one sixth of an entire circle, that is to say, it contains one complete coil and extends through about 60 degrees in addition, two circular portions 3 of the coil lying closely adjacent to each other. At one end the coil is bent radially inward as shown at 4. The two circular portions 3 of the coil which extend side by side are placed on opposite sides of the two wooden strips so placed close together on opposite sides of the fold in the cloth, the inwardly extending or radial portion 4 of the coil pressing against one of said strips, and, on account of the tension of the spring wire, which causes the adjacent circular portions 3 of the coil to lie close together, the strips 1 are firmly compressed by means of the spring rings.

I generally use three rings to each pair of strips, although in certain cases I may use less and in other cases more. Pairs of strips 55 are applied to the garment at all places where it is desired to form creases therein or

to straighten out edges thereof. For instance, as shown in Fig. 1, on each side of the garment a pair of strips 1^a may be applied on opposite sides of the upper edge of the coat collar, a pair of strips 1^b are placed on opposite sides of the front or lower edges of the coat; a pair of strips 1^c are placed on opposite sides of the front portion of the bottom edges of the garment; and a pair of strips 1^d are placed on opposite sides of the rear portion of the lower edges of the garment thereof. These strips 1^a, 1^b, 1^c, 1^d, are used for the purpose of flattening the edges of the garment. A pair of strips 1^e are placed on opposite sides of a fold in the front of each sleeve of the garment to crease the same and a pair of strips 1^f on opposite sides of a fold at the rear of each sleeve of the garment to crease the same. The outer edges of the strips of said latter pair are formed with holes 6 to receive the buttons 7 in the lower end of said sleeve. A pair of strips 1^g are placed on opposite sides of a fold in the back of the garment at each side of said back to crease the same.

A pair of strips 1^h is applied in a similar manner to the upper edge of each side of the waistcoat and a pair of strips 1ⁱ is applied to the front edge of each side of the waistcoat, one strip of said latter pair being formed with holes 8 to receive therein the buttons 9 of the waistcoat, and the pair of strips 1^d is also applied to the bottom edge of each side of the waistcoat.

In a similar manner for pressing the trousers into their proper shape there are applied the pair of strips 1^a to the upper front fold of each leg of the trousers the pair of strips 1^g to the lower front fold of each leg, the pair of strips 1^b to the upper rear fold of each leg, the pair of strips 1^f is also applied to the lower rear fold of each leg. The pair of strips 1^e is applied to the middle of the trousers between the pair of strips 1^a and 1^b above the same and 1^g and 1^f below the same, a pair of strips 1^g to the top edges of the trousers and a pair of strips 1^f to the bottom edges thereof.

It may be remarked that in some cases the same pair of strips may be used for either of two different garments. Thus the pair of strips 1^f can be used in the location for which I have designated the pair of strips 1^g.

Should the spring tension tending to press the two adjacent circular parts of

the ring together, which is the force relied upon to press the strips together and so crease the cloth of the garment therebetween, become weakened by continued use, 5 the circular portion 3 from which extend the inwardly directed or radial portions 4 may be moved to the other side of the adjacent circular portion 3 by pressing it slightly inward, or by pressing the other 10 adjacent portion 3 slightly outward, or both, and then passing the former portion inside the latter to the other side thereof. When it has been so passed to the other side, the two adjacent circular portions 3 press 15 against each other with a force which will be dependent upon the extent to which they have become bent outward from each other by continued use. Since the outward bend has now become an inward bend, toward 20 each other.

In certain cases where it may be found desirable I may use a retainer 11 for holding the cloth to a strip 1. This retainer is formed of spring wire and has a central yoke portion forming a handle 12 and terminal portions 13 which are spread apart farther than the sides of the handle and sufficiently to straddle a strip, said terminal portions being also bent out of the 25 plane of the central portion so as to engage the edges of the strip and terminating in sharp prongs 14 which penetrate the cloth without injury thereto, and thus hold the cloth in fixed relation to the strips. These 30 retainers are convenient for holding the cloth in place, and after one strip with retainers thereon has been pressed against a portion of the cloth and the prongs 14 of said retainers have been caused to engage 35 the cloth, then said retainers will hold the cloth in the proper position relative to the strip until the companion strip has been placed in its proper position to hold the cloth, and the two strips have been secured 40 together by rings 2 whereupon the retainers 11 may be withdrawn. However, by practice the user of the device will become sufficiently adept in placing the strips in position and will not need to use the 45 retainers.

16 indicates a stretcher pin formed of wire and having an elongated loop 17 and at one end a prong or pin 18 too fine to injure the cloth and at the other end a bearing member 19. This holder pin is placed 50 so that its loop 17 engages a narrow end of a strip, said loop being of such length

that it may be passed only a short distance onto the strip, it being observed that the strips taper at their ends. The pin will 60 then project beyond the strip. In addition to the loop 17 and the pin 18 said wire 16 is bent to surround the pin 18 and form a stop for limiting the passage of the pin through the cloth, and also at its other terminal portion to form a bearing 20 to bear against the side of the strip opposite to that engaged by the pin. This device is used in placing the first strip of each pair in position. The stretcher pin is placed 70 upon one end of the first strip and then engages the cloth in the proper location and holds the adjacent end of the strip in place until the other end of the strip has been brought to its proper position and the cloth 75 is folded adjacent to said strip. The other strip of the pair is then placed on the other side of the cloth and the rings placed on 80 said pair of strips in the manner before explained.

I claim:

1. In combination with one of a pair of strips for pressing therebetween the cloth of a garment, a retainer for holding said cloth to said strips consisting of a piece of wire 85 having a central yoke shaped handle, portions spaced apart and extending substantially at right angles to the plane of the handle and adapted to engage opposite edges of the strips, and terminal prongs for 90 engaging the cloth.

2. In combination with one of a pair of strips for pressing therebetween the cloth of a garment, a stretcher pin consisting of a single piece of wire having a loop-shaped 95 portion for surrounding a tapering end of the strip and of sufficient length to permit it to be passed only a short distance on said end, and terminating in a pin adapted to penetrate the cloth.

3. In combination with a flat strip which is one of a pair of strips for compressing a portion of a garment, a stretcher pin formed of a single piece of wire and comprising a loop to surround the end of the strip, a terminal pointed portion or pin to penetrate the cloth, a portion surrounding the pin to form a stop for limiting the passage of the pin through the cloth and a terminal bearing portion for bearing upon 105 the side of the strip opposite to that engaged by the pin.

ALFRED BROWN.
